UNITED STATES PATENT OFFICE.

MARTIN C. SLODERBECK, OF MARION, INDIANA, ASSIGNOR OF ONE-THIRD TO EDWARD E. LEAPLEY AND ONE-THIRD TO WILLIAM A. LEAPLEY, OF MARION, INDIANA.

AUTOMATIC DOUBLE LOCK.

1,080,787.

Specification of Letters Patent.

Patented Dec. 9, 1913.

Original application filed October 30, 1911, Serial No. 657,689. Divided and this application filed February 1, 1913. Serial No. 745,646.

To all whom it may concern:

Be it known that I, MARTIN C. SLODERBECK, a citizen of the United States of America, residing at Marion, in the county 5 of Grant and State of Indiana, have invented certain new and useful Improvements in Automatic Double Locks, of which the following is a specification.

This invention relates to certain new and 10 useful improvements in automatic double switch locks and comprises a division of my application for automatic derailler, filed October 30, 1911, Serial Number 657,689; the object being to provide a double lock in 15 which a pair of locking members are mounted, one of said members being especially adapted for locking the switch lever in locked position when trains are being switched in freight yards and the like, the 20 other lock being key-controlled in order to prevent any one from tampering with the switch after it has been set.

Another and further object of the invention is to provide an automatic double lock 25 which is exceedingly simple and cheap in construction and one in which the parts are so mounted and inclosed in a casing, that all danger of the same being affected by the weather, is prevented.

30 Another and further object of the invention is to provide novel means for actuating the sliding bolt by a treadle.

Other and further objects and advantages 35 of the invention will be hereinafter set forth and the novel features thereof defined by the appended claims.

In the drawing—Figure 1, is a side elevation of my improved double lock, one side plate being removed in order to show the 40 mechanism thereof; Fig. 2, is an end view of the lock; and Fig. 3, is a side elevation taken from the reverse side to that of Fig. 1; the side plate being removed to show the locking mechanism.

45 Like numerals of reference refer to like parts in the several figures of the drawings.

In carrying out my improved invention, I employ a casing 1 mounted upon a suitable base; said casing being provided with a 50 pair of compartments to each side of the lever-receiving slot 3. Mounted in one of the compartments is a sliding bolt 4 which is provided with an oblique edge 5 mounted upon an inclined face 6 formed in the com-

partment; said bolt having an oblique upper 55 edge 7 adapted to be engaged by the switch lever 8 when forced into the slot so as to force the bolt out of its path which allows the lever to pass into the lower portion of the slot. The bolt 4 is provided with a 60 notch 9 into which extends the rounded end 10 of a lever 11 pivotally mounted as shown at 12, and provided with a weighted end 13 which normally holds the bolt in an extended position into the slot so that after the 65 lever has passed into the lower portion of the slot, the bolt is forced into the position shown in Fig. 1. When the bolt is engaged by the lever it is moved into the position shown in dotted lines in Fig. 1; and in Fig. 70 1, I have shown the side of the casing removed which comprises a plate 14 secured in position by bolts 15. Mounted in the other compartment of the casing 1 is a sliding bolt 16 normally held in an extended 75 position across the slot 3 by a spring 17 arranged between pins 18 and said bolt is provided with an oblique face 19 which is engaged by the lever 8 when forced into the slot so as to force the bolt out of its path 80 and after the switch lever has passed the bolt, it is thrown back into position so as to hold the switch lever in locked position. The bolt is provided with a notch 20 adapted to receive the bit of a key 21 capable of 85 being inserted through a keyhole formed in the side of the casing; said keyhole being normally inclosed by a swinging cover 22 in order to prevent snow and rain from entering the casing. It will be seen that 90 when the key is inserted in the lock and turned, the bolt 16 will be moved or drawn out of the lever-receiving slot in order to allow the lever to be raised upwardly.

In order to provide means for locking the 95 bolt 16 without the key, I provide the bolt with notches 23 into which is adapted to fit the lug 24 of a dog 25 carried by a treadle 26 pivotally mounted in a bracket 27. By raising the treadle, the dog will be forced 100 into engagement with the locking bolt in order to force the lug 24 into the notch so as to lock the bolt 16 in extended position. When the bolt 16 is locked by the dog 25 it is only necessary to press downwardly on 105 the treadle 26 in order to release the dog so as to allow the bolt 16 to be moved out of the path of the switch lever as the same

is forced into the slot, which is clearly shown in dotted lines in Fig. 3.

From the above description, it will be seen that I have provided an automatic double lock for switch levers in which means is provided for temporarily locking the switch lever by a sliding bolt controlled by a weighted lever; positive means being provided for locking the switch lever by a sliding key-operated bolt.

I claim:

1. An automatic double lock for switch levers comprising a casing having a lever-receiving slot, a weight-actuated bolt mounted in said casing normally held in extended position over said slot, a spring-actuated bolt mounted in said casing held in extended position over said slot, and a key for actuating said spring-actuated bolt.

2. An automatic double lock for switch levers comprising a casing provided with a lever-receiving slot and a pair of compartments, one compartment being provided with an inclined guide, a bolt slidably mounted upon said guide, and a weighted lever for actuating said bolt.

3. An automatic lock for switch levers comprising a casing provided with a lever-receiving slot, a bolt slidably mounted in said casing extending across said slot, a spring for holding said bolt in extended position, said bolt being provided with a notch, and a key having a bit co-acting with said notch for locking said bolt in extended position.

4. A lock for switch levers comprising a casing provided with a lever-receiving slot, a bolt slidably mounted in said casing, a

spring for holding said bolt in extended position across said slot, a pivoted lever, and a dog carried by said lever co-acting with said bolt.

5. A lock for switch levers comprising a casing provided with a lever-receiving slot, a spring-actuated bolt provided with notches, a pivoted treadle, and a dog pivotally carried by said treadle provided with a lug co-acting with said notches.

6. An automatic double lock for switch levers having a weight-actuated bolt and a spring-actuated bolt, said spring-actuated bolt being locked in extended position by a pivoted dog, and means for actuating said dog.

7. An automatic double lock comprising a casing provided with a lever-receiving slot, said casing being provided with compartments, a weight-actuated bolt slidably mounted in one of said compartments, a spring-actuated bolt mounted in the other compartment, and double means for locking said spring-actuated bolt in extended position across said slot.

8. A switch lever lock comprising a casing provided with a lever-receiving slot, a spring-actuated bolt provided with a notch, a pivoted dog having a lug co-acting with said notch, and a treadle for actuating said dog.

In testimony whereof I affix my signature in presence of two witnesses.

MARTIN C. SLODERBECK.
